CATHODE RAY TUBE

Philo T. Farnsworth, San Francisco, Calif., assignor, by mesne assignments, to Farnsworth Television & Radio Corporation, Dover, Del., a corporation of Delaware

Application June 1, 1936, Serial No. 82,887

2 Claims. (Cl. 250—161)

My invention relates to oscillographic tubes, and more particularly to an oscillographic tube wherein a luminous spot of small size may be produced.

5 Among the objects of my invention are: to provide an oscillograph capable of producing a luminous spot of small size to provide a means for maintaining electrons in an oscillographic tube in parallel array between cathode and screen; to provide a means in an oscillographic tube for preventing dispersion of electrons between cathode and screen; to provide a concentrating means acting on the electron beam in an oscillographic tube; to provide a means in an oscillographic 10 tube for applying a magnetic field directed to maintain electrons in parallel relationship between cathode and screen; to provide a simple and efficient oscillographic tube having high definition, and to provide an internal concentrating 15 coil in a cathode ray tube.

20 Other objects of my invention will be apparent or will be specifically pointed out in the description forming a part of this specification, but I do not limit myself to the embodiment of the invention herein described, as various forms may be adopted within the scope of the claims.

In the drawing:

Figure 1 is a plan view of the envelope of the oscillograph of my invention, showing diagrammatically a preferred beam deflecting means.

Figure 2 is a sectional view of the electron gun and concentration device utilized in the tube of Figure 1.

It is well known in the art that a cathode ray oscillograph tube, essentially comprises a means for producing electrons such as a thermionic cathode, and a luminescent screen against which electrons from the cathode may be projected in such a manner as to produce a small luminescent spot upon impact. Deflection means, either magnetic or electrostatic, may then be used to move the spot over a defined area of the screen within the time limit of vision, so that either a trace or a picture field may be described. All of these prior art devices, however, have a common fault, namely, that electrons, being negative in charge, tend to repel each other within the beam, and, as a consequence, the beam in many cases diverges during its passage from cathode to screen 45 to such an extent that the spot energized by impact on the screen becomes so large and diffused that a sharp, well defined trace cannot be secured. Furthermore, accelerating anodes tend to cause even greater dispersion. Certain expedients have heretofore been used to prevent such

dispersion. For example, a trace of inert gas may be left in the tube and the beam focused by the action of the gas. In other cases electrostatic electron lenses have been used, but I have found that it is possible to maintain a concentrated beam by sealing within the tube a small electromagnetic coil in such a position that when energized its magnetic field will extend in the direction of electron travel in the beam or, inasmuch as all elements are usually lined up along the axis of the tube, the coil will be co-axial with the means for producing the beam, and the screen.

My invention may be fully understood by direct reference to the drawing. Here an envelope 1 of the usual flask shape is provided at the large end with a fluorescent screen 2 deposited on the inside of the glass wall. This fluorescent screen may be of willemite or any other known fluorescent or luminescent material. At the small end of the tube, mounted on a stem 3, is an electron gun comprising an electron emitting cathode 4 which may be either directly or indirectly heated, surrounded by a control electrode 5 having an axial aperture 6, through which electrons may pass to enter the adjacent opening of an apertured cylindrical anode 7. The anode 7 is surrounded by a magnetic coil 8, which is preferably sealed in a glass tube 9 of toroidal shape so that the anode 7 lies firmly fixed in the central aperture thereof. Leads from coil 8 are brought out through the wall of the glass tube 9, and the combined coil, glass tube, and anode assembly is supported on risers 10 and 11, which are attached to bands 12 and 13 respectively, clamped around stem 3. Leads to bands 12 and 13 are brought to the outside of the envelope as are leads from the grid 5 and cathode 4. Riser 10 connects not only to one end of coil 8 but also to anode 7, and riser 11 connects to the other end of coil 8.

In operation the cathode 4 is heated by cathode battery 14, thus causing an emission of electrons. Anode 7 is energized to a positive potential from anode battery 15, and a small portion 16 of this battery is utilized to pass current through coil 8 by being connected thereto through riser 11. The anode tube 7, being energized to a positive potential with respect to cathode 4, draws electrons therefrom through it and projects them against screen 2. The current, however, flowing through coil 8 from battery 16, causes a strong magnetic field to be formed extending co-axially with the path of the electrons through the anode, thus keeping the electrons in a parallel stream and concentrating them on the screen. The electrons, therefore, both entering and leaving anode

- 7 are under the influence of this magnetic field, and therefore the stream as it leaves anode 7 going toward the screen tube tends to become concentrated, and any dispersion caused by the anode 8 field or by their own inherent charges is greatly reduced, and a small, well defined spot is thus obtained.
- While I have shown my coil 8 enclosed in the glass tube, this, of course, is not always necessary.
- 10 If insulated wire is utilized for coil 8 it is desirable to seal it within a tube in order that the organic materials utilized for insulation may not contaminate the vacuum within the tube. If, however, it is desirable that coil 8 be not sealed with
- 15 in the special tube, bare wire may be wound on an insulating form and spaced to prevent short circuited turns. Even in this case it may be desirable to utilize glass for the form. In any event, the main feature of my invention is that a magnetic coil is placed between cathode and screen so that a defined spot may be obtained, and I do not wish to be limited to any particular location of coil 8 with respect to the electrodes except that coil 8 shall be positioned co-axial with the path of
- 20 the electrons between cathode and screen in the undeflected portion of the path. This, naturally, means that the cathode, anode, screen and coil, shall be in co-axial relationship.
- 25 If the oscillograph is to be used to define

a trace which varies in light intensity, then it is desirable that the strength of the electron beam be varied. Control electrode 5 may be energized from an input line 17 so that the strength of the beam may be varied in any convenient manner. I have also shown the beam as being deflected in two directions by magnetic coils 18 and 19, energized respectively by oscillators 20 and 21.

An oscillograph made as herein described will give a wide field of view and sharp definition. It is, therefore, ideally adapted for use in a television receiver, or like systems.

I claim:

1. A cathode ray tube comprising an enclosing vessel, a cathode adapted to emit a stream of electrons and supported at one end of said vessel, a fluorescent screen at the other end of said vessel, an anode having a central beam canal opening at one end toward said cathode and at the other end toward said screen, an annular hollow gas-tight enclosure surrounding said anode, means for supporting said enclosure from said vessel, and an electromagnetic coil within said enclosure and also surrounding said anode.

2. Apparatus in accordance with claim 1, wherein the inner wall of said gas-tight enclosure is closely adjacent said anode and forms the chief positioning structure thereof.

PHILO T. FARNSWORTH.
